UNITED STATES PATENT OFFICE

158,349

ARTIFICIAL FISHING LURE

Raymond Wiinikka, Grand Rapids, Mich.

Application August 8, 1949, Serial No. 4,363

Term of patent 14 years

(Cl. D31—4)

To all whom it may concern:

Be it known that I, Raymond Wiinikka, a citizen of the United States, residing at Grand Rapids, in the county of Kent and State of Michigan, have invented a new, original, and ornamental Design for an Artificial Fishing Lure, of which the following is a specification, reference being had to the accompanying drawing, forming part thereof.

Figure 1 is a top perspective view of an artificial fishing lure, showing my new design;

Figure 2 is a bottom perspective view;

Figure 3 is a front end elevational view thereof; and

Figure 4 is a rear end elevational view of the same.

I claim:

The ornamental design for an artificial fishing lure, as shown.

RAYMOND WIINIKKA.
